JOHN C. WILSON-HUGHES, OF LOWELL, MASSACHUSETTS.

GAME DEVICE.

1,248,970.

Specification of Letters Patent.

Patented Dec. 4, 1917.

Application filed January 29, 1917. Serial No. 145,147.

To all whom it may concern:

Be it known that I, JOHN C. WILSON-HUGHES, a citizen of Great Britain, residing at Lowell, in the county of Middlesex and State of Massachusetts, have invented certain new and useful Improvements in Game Devices, of which the following is a specification.

This invention relates to games of the type wherein a ball or similar article which is capable of being thrown without injury, is bounced from a substantially level playing surface into one of one or more receptacles or stalls which may or may not have 10 different values in figuring up the score of each player.

I am aware that games have been devised wherein a resilient ball is to be bounced from a substantially dead playing surface. 20 My invention is of the type wherein the ball may be non-elastic or substantially so, and the playing surface is resilient. I prefer to use a wooden ball, and for a playing surface, to secure silence, resiliency and adjustability, a net with a relatively large 25 mesh.

My purpose is to provide a silent resilient playing surface of such character that it and its attachments can be folded compactly with 30 great rapidity or can be extended into playing position with equal facility.

In the drawings Figure 1 is a perspective view of my game in position for playing. Fig. 2 shows in perspective the side guards 35 and legs folded in, and the frame half folded. Fig. 3 shows in perspective, the frame completely folded. Fig. 4 is a plan detail view of my preferred type of elevated stalls. Fig. 5 shows in perspective, detail 40 of one of the folding legs. Fig. 6 is a plan view of a modification of the device extended for playing. Fig. 7 shows this form about to be folded. Fig. 8 is a detail perspective view showing a method of attaching the net 45 to the side bars. Fig. 9 is an elevation of a detachable set of stalls.

In the drawings, 10 and 11 are the side bars of one rectangular frame, and 20 and 21 of the other. 12 and 13 are the cross bars of one frame and 22 and 23 of the other. These cross bars are preferably of rectangular cross section. I will call 13 and 22 the 50 inside cross bars, and 12 and 23 the outside cross bars which are set in from the outside

ends of the side bars to permit rollers 40 and 55 41 to be located so as to extend across the front and back outside ends of the playing surface.

Side bars 10 and 20 are hinged together 60 at 14, and 11 and 21 at 15, both hinges being preferably at the bottom.

At or near the junctions of cross bar 23 with side bars 20 and 21, and of cross bar 12 with side bars 10 and 11, I will call the outside corners of the frame, and near these 65 corners I locate foldable legs which may be of any desired type.

I prefer to utilize for legs, the adjusting pegs for tightening and locking the stretching rollers 40 and 41. Each peg 42 consists 70 of a wire rod angularly bent at a right angle to form a peg part and a handle or leg part 43.

Each stretching roll has one or more holes 75 44, 45 through which a peg can pass into an adjoining hole 46 in an outside cross bar thus locking the roller.

To use as a leg, the part 43 must be long enough to extend below the frame, and to hold it in the down position, I prefer to cut 80 a slot 47 from each roller hole into which 43 can be pushed as shown in Fig. 5 to keep it from turning. I may use a rubber cap 49 on the end of each leg.

The inside cross bars 13 and 22 are far 85 enough apart to permit a ball such as B to drop in between them, and each carries, in staggered relation, projections such as 24 and 25 which form between them stalls open at the top from which, when a ball drops 90 therein, it cannot escape. When the device is folded, these stalls being so divided, part being carried by one frame, and part by the other, are out of the way and the projections 24 and 25 being relatively slight, are not 95 likely to be knocked off.

A resilient net N is stretched over the bottom part of both frames and between stretching rollers 40 and 41. It may be slidably or otherwise fastened to the side bars 10, 11, 100 20, 21, and to the inside cross bars 13 and 22, but should not be attached to the outside cross bars 12 and 23. This net preferably extends under the bottom of the frame so that the stalls between 24 and 25 shall be 105 elevated above it. The rollers 40 and 41 may be locked in position by any suitable device. The one shown comprises pegs 42 each of

which extends through a suitable hole in each roller and into any suitable hole in an adjoining outside cross bar. One or more holes may be pierced in each roller to permit of adjustment by these pegs.

By using a resilient large meshed net, I can fasten it along the bottom of the frames all the way around, or I can leave it loose on the sides. I prefer to attach it to the side bars in the manner shown in Fig. 8 wherein a cleat 18 is threaded through the meshes of the net, and is then lightly tacked in place by means of nails 19. This leaves a channel between the side bar, such as 11 and cleat 18, through which the net can slip while being tightened.

Cleats similar to 18 are preferably used at the bottom of inside cross bars 13 and 22, and being loosely tacked in place, permit the net to slip while being tightened, whereby it can be kept taut at the bottom of the stalls under projections 24 and 25. While it is kept taut, a ball is likely to bounce out if it bounces in, thus adding to the interest of the game.

I prefer to use also foldable side guards G, G, G, G, one of which is pivoted on each side of each frame so as to be foldable down on top thereof as shown in Figs. 2 and 3. As shown, each guard consists of a three sided rectangular metal rod 60, 61, 62 which is bent in at each end 63 and 64 to enter a suitable hole in a cross bar such as 22, 13, 12 or 23. This bent rod is covered with netting or other suitable material 65. This netting 65 is preferably allowed to be slack so that if the balls strike it, they will be caught and held.

As shown in Figs. 2 and 3, I prefer that these guards shall be high enough so that when folded, they almost meet, whereby together with the rest of the frame and the net, they form a cage to receive and hold the balls B when the device is folded.

In Figs. 6 and 7, I show a modified construction in which the side bars 70, 71, 72, 73 are hinged together, and the outside bars 12 and 23 together with the rollers 40 and 41 are substantially the same as in the other construction, but the inside cross bars 74 and 75 come close together and are connected to 12 and 23 by longitudinal brace bars 76 and 77.

These bars 74, 75, 76, 77 are preferably not as high as 12, 23, 70, 71, 72, 73 whereby the sets of stalls 80 and 81 in which each stall is shown as circular, can be set down with their tops flush with the tops of the side bars. Stalls 80 and 81 are carried by split disks 86 and 87 which may each be fixed to bars 74, 76 and 75, 77 respectively, the middle stall 82 being split as shown in Fig. 6. No side guards are shown in this construction.

The legs 33 shown in this construction are

of a well known folding type while the pegs 32 are the same as 42 except that the handle part is too short to serve as a leg.

In Fig. 9, I show a variation of this construction in which 83 is a solid disk of paste board, or other material, from which project downwardly, spring fingers 84 which permit it to be readily attached to or detached from the inside cross bars 74 and 75. In this construction, the stalls 82 are shown as quite deep. I prefer that the two ends of the playing surface, and the two frames shall slope toward the inside or center as the ball is less likely to get out of control with this arrangement. This slope is usually a natural result of the wooden construction.

I also prefer to provide a strap S which may be fastened to a suitable button or knob 38 and is of such length that it can pass entirely around the folded frame, thus holding all parts in the closed position.

My game is played by throwing the ball from the hand or otherwise onto the netting in such manner that as shown by the dotted line in Fig. 1, it will rebound into one of the stalls between 13 and 22, or 80, 81, or 82 as shown in the other construction. These stalls may be numbered or painted to indicate a different value or a penalty.

A dead ball used on a resilient playing surface is much better to use indoors than a live, resilient ball on a dead surface.

The stalls shown in Fig. 9 may be slipped on the frame when it is upside down, in which case the legs have no function.

I claim:

1. A game apparatus having a resilient playing surface formed of two rectangular frames each of which has side bars and a front and back cross bar, the side bars of one being hinged to the side bars of the other, stretching rollers which extend across the outside ends of the playing surface, a resilient net which extends between the side bars and is attached to the rollers, inside bars with projections which form one or more stalls each open at the top and elevated above the net, and adjusting pegs for the rollers which serve also as legs.

2. A game apparatus having a resilient playing surface, formed of two rectangular frames each of which has side bars and an inside and outside cross bar, the side bars of one being hinged to the side bars of the other, stretching rollers which extend across the outside ends of the playing surface, a resilient net which extends between the side bars and is attached to the rollers, together with inside cross bars proximate the hinged ends of the side bars each having one or more projections which form stalls open at the top, and foldable legs as described.

3. In a game apparatus, the combination of two rectangular frames each having re-

silient netting stretched thereon and hinged together, with foldable side guards, and stalls open at the top and elevated above the net proximate the junction of such frames, together with foldable legs at the outside corners of the frames.

4. A game apparatus having a resilient playing surface formed of two rectangular frames each of which has side bars and in-
10 side and an outside cross bar, the side bars of one being hinged to the side bars of the other, stretching rollers which extend across the outside ends of the playing surface, a resilient net which is stretched between the rollers, together with one or more stalls each open at the top and elevated above the net.

5. A game apparatus having a resilient playing surface, formed of two rectangular frames each of which has side bars and a front and a back cross bar, the side bars of one being hinged to the side bars of the other, stretching rollers which extend across the outside ends of the playing surface, a resili-
20 ent net which is stretched between the rollers, together with one or more stalls each open at the top and elevated above the net, such stalls being so divided that part are carried by one frame and part by the other.

6. A game apparatus having a resilient playing surface formed of two rectangular frames each of which has side bars and an inside and an outside cross bar, the side bars of one being hinged to the side bars of the other, stretching rollers which extend across
30 the outside ends of the playing surface, and cleats lightly tacked along the bottom of the side bars, together with a resilient net which is attached to the stretching rollers

and is threaded on to the cleats, and inside cross bars proximate the hinged ends of the side bars each having one or more pro-
40 jections which form stalls open at the top.

7. A game apparatus having a resilient playing surface formed of two rectangular frames each of which has side bars and an inside and an outside cross bar, the side bars of one being hinged to the side bars of the other, stretching rollers which extend across
45 the outside ends of the playing surface, and cleats lightly tacked along the bottom of the side bars, together with a resilient net which is attached to the stretching rollers and is threaded on to the cleats, foldable side guards carried by the side bars of such size as to almost touch when folded, and in-
50 side cross bars proximate the hinged ends of the side bars each having one or more projections which form stalls open at the top.

8. A game apparatus having a resilient playing surface formed of two rectangular frames each of which has side bars and an inside and an outside cross bar, the side bars of one being hinged to the side bars of the other, stretching rollers which extend across
60 the outside ends of the playing surface, a resilient net which is stretched between the rollers, together with one or more stalls each open at the top and elevated above the net,
65 and angularly bent adjusting pegs each of which passes through a roller into an outside cross bar and has a part adapted to serve as a leg.

In testimony whereof I affix my signature.

JOHN C. WILSON-HUGHES.
